UNITED STATES PATENT OFFICE.

CARL LAWRENCE MATTISON, OF ROCKFORD, ILLINOIS, ASSIGNOR TO MATTISON MACHINE WORKS, OF ROCKFORD, ILLINOIS, A CORPORATION OF ILLINOIS.

SAFETY DEVICE FOR SAWING MACHINES AND THE LIKE.

Application filed December 26, 1924. Serial No. 758,043.

To all whom it may concern:

Be it known that I, CARL LAWRENCE MATTISON, a citizen of the United States, residing at Rockford, in the county of Winnebago and State of Illinois, have invented a certain new and useful Safety Device for Sawing Machines and the like, of which the following is a specification.

The invention pertains to a combination 10 guard and safety device for a power-actuated rip-sawing machine or the like, and the object of the invention generally stated is to produce a device associated with the work discharging mechanism for guarding 15 the receiving attendant against injury and for protecting the machine against injury due to the work or any portion thereof becoming caught or clogged in the machine as it is being discharged therefrom.

20 In the accompanying drawings Figure 1 is a fragmentary vertical sectional view through the rear end of a rip-sawing machine embodying my invention.

Fig. 2 is a fragmentary side elevational 25 view of the rear end of the machine, this view being taken on a somewhat smaller scale than Fig. 1.

Fig. 3 is a fragmentary plan view of the portion of the machine shown in Fig. 2.

30 The machine selected for purposes of illustration comprises a main or base frame 7 constructed to provide a runway 8 in its top for a feed chain 9. This chain comprises in the present instance a series of blocks 10 linked together and running over a driving sprocket 11 mounted at the rear end of the machine and connected with a suitable source of power. The lower run of the chain in passing from the sprocket wheel 11 35 passes through an opening 12 in the rear end of the frame and thence forwardly through the frame for connection with the sawing mechanism (not shown).

40 In use the machine is customarily attended by an operator stationed at the front end of the machine, who feeds the work into the machine, and also by a person stationed at the rear end of the machine for receiving the work as it is discharged. Of these two attendants, the one receiving the work is an unskilled workman, usually a boy lacking in experience and discretion, or an elderly man likely to be slower in action and perception. It is desirable therefore to provide means adapted to prevent injury to

such operators or to the machine in the discharge of the work, and I have provided such a means in the form of a housing enclosing the discharge end of the feed chain and so mounted as to be capable of yielding, in the event that the hand or fingers of the attendant should become caught between the chain and the top plate of the housing, or in the event that the work or some part thereof may in the operation of being discharged engage such top plate of the housing or become clogged between it and the chain.

The means herein shown for accomplishing this result comprises a housing 13 open 70 at its forward side, and having opposite side and rear walls shaped to conform to the curvature of the chain passing over the sprocket wheel 11. Thus the lower portion of the housing curves downwardly and forwardly, and the housing as a whole is mounted for movement relative to the main frame. Herein its lower end is pivotally mounted as at 15 upon a bracket 16 bolted to the rear end of the machine frame a short 75 distance below the sprocket wheel and the opening 12 through which the chain passes forwardly to the sawing mechanism. The upper end of the housing 13 has a top wall 17 upon the upper side of which is secured a guard plate 18 which is preferably formed 80 of wood. This plate extends forwardly over the chain just as the latter begins to descend in its passage around the sprocket wheel 11, a slight space being provided between the 85 forward end of the plate 18 and the chain for clearance purposes. Preferably the forward edge of the plate is sharpened or tapered as indicated at 19 so as to guide the leading edge of the work upwardly onto the 90 plate 18.

95 It sometimes happens, however, that the work contains a knot or splinter which projects downwardly far enough to strike the forward edge of the plate 18, or the work 100 may otherwise become caught between the plate 19 and the feed chain. When this plate, under these circumstances, is held stationary as is the case with prior art machines, such a clogging of the work necessitates an abrupt stopping of the machine to 105 prevent injury thereto. Also it sometimes happens that the receiving attendant will, in removing work from the machine, place his fingers over the forward end of the plate 19 110

in such a manner as to cause them to be carried downwardly between the plate and the chain. I therefore provide spring means normally holding the housing in an upright 5 position with its lower forward side engaging a shoulder 20 on the bracket 16 (Fig. 3). The spring means consists in the present instance of a pair of coiled contractile springs 21, one on each side of the housing 10 and having their opposite ends anchored to studs or pins 22 and 23 on the housing and bracket respectively.

It will thus be seen that if the fingers of the attendant should become caught between the forward end of the plate 19 and the feed chain, he can readily dislodge them by pulling rearwardly on the plate causing the housing to swing rearwardly and downwardly against the action of the springs 21; 20 likewise, if the work becomes clogged in the passage of the chain downwardly into the housing 13, the latter will yield to prevent injury to the machine.

Preferably the springs 21 are so arranged 25 with respect to the pivotal connection 15 between the housing and the bracket 16 that the housing may be swung downwardly to carry the pins 22 past center so that the housing will be held by the springs in its 30 open position permitting free access to the rear end of the feed chain and associated parts.

I claim as my invention:

1. In a machine of the character described, 35 the combination of a main frame, work discharge mechanism including a wheel mounted on the frame and a chain extending horizontally along the top of the frame, thence downwardly over the wheel and forwardly therefrom, a guard pivotally supported on the frame and adapted to enclose said wheel and chain passing thereover, the guard including a top over which the work 40 is normally adapted to slide and beneath which the chain passes around said wheel, and spring means normally holding the 45 guard in operative relation to said chain and wheel but permitting the guard to yield rearwardly away from the chain.

2. In a machine of the character described, 50 the combination of a main frame, work discharge mechanism including a wheel mounted on the frame and a chain extending horizontally along the top of the frame and then downwardly over the wheel, a housing pivotally supported on the frame and adapted to enclose said wheel and chain 55 passing thereover, the housing further having a top plate over which the work is normally adapted to slide and beneath which the chain passes around said wheel, and

spring means normally holding the housing in operative relation to said chain and wheel but permitting the housing to yield rearwardly away from the chain, said spring 65 means comprising a coiled contractile spring connected at opposite ends to the frame and to the housing, the arrangement being such that the end of the spring secured to the housing is capable of swinging from one side 70 to the other of the pivotal connection between the housing and the frame whereby to hold the housing in either operative or inoperative relation to the frame.

3. A machine of the character described 75 having, in combination with a main frame, work feeding means including an endless chain and a wheel mounted in the discharge end of the frame, the arrangement being such that the upper portion of the chain 80 travels horizontally along the top of the frame and thence downwardly around the wheel and forwardly through the frame, a bracket secured to the frame below said wheel and providing a stop shoulder, a housing movably supported on said bracket and adapted to enclose said wheel and the portion of the chain passing thereover, said housing having a top plate over which the work is normally adapted to slide as it 85 is moved rearwardly by the chain, and spring means operating to hold said housing with a portion thereof abutting against said stop shoulder.

4. A combined guard and safety device 95 for rip-sawing machines and the like comprising a housing substantially arcuate in form and having opposite side and rear walls and a rigid top plate adapted to enclose the rear or discharge portion of an endless conveyor operating to discharge work from the machine so as normally to slide over said top plate, said housing being mounted on the machine for movement from a normal 100 operative position away from the conveyor, and spring means operating normally to hold the housing in operative association with the discharge end of the conveyor.

5. A combined guard and safety device 110 for rip-sawing machines and the like comprising a housing adapted to enclose the rear or discharge portion of an endless conveyor operating to discharge work from the machine over the top of the housing, said housing being mounted on the machine for 115 yielding movement from a normal operative position in the direction of movement of the conveyor.

In testimony whereof, I have hereunto affixed my signature.

CARL LAWRENCE MATTISON.
